UNITED STATES PATENT OFFICE.

JOHN L. ALBIEZ, OF PITTSBURGH, PENNSYLVANIA.

BLOOMING MILL.

Application filed September 21, 1920. Serial No. 411,742.

To all whom it may concern:

Be it known that I, JOHN L. ALBIEZ, a citizen of the United States, and residing in the city of Pittsburgh, in the county of Allegheny and State of Pennsylvania, have invented or discovered new, useful, and Improved Blooming Mills, of which the following is a specification.

My invention consists in new and useful 10 improvements in blooming mills used for the breaking down or preliminary reduction of metal blooms.

The present method of breaking down blooms is to pass the same through a series 15 of two roll blooming mills, each pass reducing the thickness of the bloom in one direction, and the bloom being usually turned 90° after each pass. This method of course requires a number of mills, each with its own 20 crew, and the operation is both expensive and time consuming.

My object is to provide a single blooming mill with which the entire breaking down process can be accomplished, the services of only a single crew being required.

For this purpose I provide a four roll mill, two of the rolls being horizontal and two vertical, so that all four rolls work on the bloom at one and the same time.

20 The rolls are journaled in adjustable bearings so as to be movable in relation to the common center, and, thus, by successive passes to accomplish the progressive reduction of the bloom.

30 I provide common, power-actuated means for shifting the rolls so that the adjustment of the same in relation to the common center may be uniformly accomplished and without requiring the stoppage of the mill.

40 I prefer to apply rotative power to the two horizontal rolls, and to drive the vertical rolls from the former, all of said rolls being provided with bevelled gear teeth which intermesh together, thereby distributing 45 the strains and avoiding torsional twists.

Other novel features of construction and arrangement of parts will appear from the following description:—

In the accompanying drawings, which are 50 however merely intended to illustrate the principles of my invention without limiting the scope of the same to the construction shown. Fig. 1 is an elevation of a blooming mill embodying the principles of my invention, the same being partially broken away in vertical section to show parts; Fig.

2 is an end view of the same looking toward the right in Fig. 1, and likewise partially broken away in section, and Fig. 3 is a detail showing the inner face of one of the 60 frame standards.

The following is a detailed description of the drawings.

The frame of the mill may be of any convenient construction. For the sake of illustration I have shown it comprised of a bed plate A which may be secured on a proper foundation and upon which are slideably mounted a pair of bases B from each of which upwardly extend twin standards C. 65 The bases B are fixable in any adjusted position by any convenient means, not shown.

The adjacent faces of each pair of standards C are channeled to form parallel, vertical edge ribs 1 and the intervening recess 70 or channel 2.

3 and 3^a represent, respectively, housings slideably mounted between the pairs of standards C, the ends of said housings fitting into the channels 2, so that the ribs 1 80 guide the same in their movements and hold them in place on the standards.

The necks of the upper horizontal roll D are journaled in the housings 3, while the necks of the lower horizontal roll D' are 85 journaled in the housings 3^a.

4 and 4^a represent, the housings for the vertical rolls E E', respectively:

Said housings are shown provided with inwardly extending top and bottom portions 90 provided with bearings 5 in which the necks of said vertical rolls are journaled.

Said housings are supported between the pairs of standards C by means of top and bottom cross bars 6 whose ends are horizontally notched or recessed to slidably engage the horizontal ribs 7 in the standards, thereby permitting the rolls E and E' to be shifted horizontally.

The ends of all of the rolls are provided 100 with deep bevelled gear teeth which intermesh so that the rolls rotate in unison, the teeth being of sufficient depth that the rolls may be shifted to a relatively great degree without destroying the power transmission 105 between the rolls. In the case of the vertical rolls I have shown the gear teeth 8 cut into the material of the roll but in the case of the horizontal rolls I have shown the teeth formed on separate collars 9 which are 110 keyed and pinned to the necks of the rolls. Either construction may be adopted.

Inside of the gear teeth I prefer to provide the rolls with bevelled end surfaces 10 which, when the rolls are adjusted for the final pass, bear lightly on each other 5 and thus reduce any edge fins which may have been formed on the bloom during previous passes.

The necks of the two horizontal rolls D and D' at one end are provided with large 10 gear wheels 11 of equal diameter which intermesh thus driving the two horizontal rolls in opposite directions at the same speed. Power from a convenient source is applied to one or both of said gears 11.

15 It is evident that the vertical rolls E and E' are driven, in opposite directions to each other, from the horizontal rolls. The bevelled gear connection between the rolls is such that the peripheral speed of all four 20 rolls is the same.

The tops of each pairs of standards C are connected together by cap plates 12 which may be bolted in place.

The lower housings 3^a are supported by 25 the threaded shafts 13 whose flat heads are bolted to the under faces of the housings and whose lower ends engage vertical bearing holes 14 in the bases B. 15 represents a worm gear having a threaded bore by 30 means of which one of said gears is screwed on each of the shafts 13. Said gears are held against vertical movement by means of boxes 16 secured on the bases B.

17 is a shaft horizontally journaled in 35 bearings 17^a on the bases B and provided with worms 17^b and mesh with the gears 15. F represents a reversible electric motor or other source of power, so that the shaft 17 may be rotated to either raise or lower the 40 lower roll D'.

18 represents a vertical shaft at either end of the mill journaled in bearings 19 carried by the standards C. The shaft 17 is provided with two bevelled gears 20 meshing with similar gears 21 mounted on the lower ends of the shafts 18. The upper ends of the shafts 18 are provided with similar gears 22 which mesh with similar gears 23 on the ends of the shaft 24 horizontally journaled in bearings 25 mounted on the cap plates 12.

The housings 3 of the upper horizontal roll D are suspended by means of screw shafts 26 whose lower ends are provided 55 with squared heads which seat in recesses cut in the under faces of the plates 27 bolted to the tops of the housings, said shafts extending up through holes in said plates and also through holes in the cap plates 12.

60 28 are worm gears whose threaded bores are screwed onto the upper ends of the shafts 26 and which are prevented from vertical movement by boxes 29 mounted on the cap plates 12. 30 are worms on the shaft 24 meshing with said gears 28, whereby the 65

roll D may be raised or lowered by the proper rotation of the shaft 24.

31 represents threaded shafts rigidly attached to and extending horizontally from the housings 4 and 4^a, and 32 represents 70 worm gears whose threaded bores are screwed on said shafts 31 and which are held from horizontal movement by boxes 33 mounted on the standards C. The gears 32 are in mesh with worms 34 on the shafts 18, wherefore the rolls E and E' are shiftable horizontally by the proper rotation of the shafts 18.

The gears 20, 21, 22, 23, 15, 28 and 32 and the worms 17^b 30 and 34 are so proportioned and assembled that by the rotation of the shaft 17 in the proper direction the four rolls may be moved in unison away from or toward their common center.

The operation of my improved mill is as follows:

The four rolls are moved away from their common center to the proper degree to receive and give the blooms the first breaking down pass, and the mill is started, and 90 the bloom run through. The bloom is then given the required number of passes to reduce it to the desired dimensions, the rolls being moved toward the common center before each pass to procure the necessary reduction, adjustment of the rolls being 95 quickly made without stopping their revolution.

It is probable that until the rolls reach their innermost position, shown in Fig. 1, 100 corner fins will be formed on the bloom, but these are not material, and are removed by the final pass, as has already been explained.

It is evident that my improved mill makes 105 possible a very substantial economy in equipment and mill space inasmuch as only a single mill is required instead of the series of blooming mills now necessary. Consequently a great saving in the number of 110 men used is also effected, and further a corresponding saving in the time required for breaking down the blooms.

Although, for the sake of clearness, I have minutely described the illustrative embodiment of the principles of my invention shown in the drawings, I do not wish to limit myself thereby, but claim broadly:—

1. In a blooming mill, the combination of a pair of horizontal rolls and pair of vertical rolls disposed in relation to a common center, means for applying rotative power to each of said four rolls, and means for shifting said rolls in unison in relation to said common center, substantially as described.

2. In a blooming mill, the combination of a pair of horizontal rolls and a pair of vertical rolls disposed in relation to a common center, means for applying rotative power 130

to each of said four rolls, movable housings for said rolls, and common means for shifting said housings, whereby said rolls may be moved in unison in relation to said common center, substantially as described.

3. In a blooming mill, the combination of a frame, a pair of horizontal rolls, housings for said horizontal rolls movable in a vertical plane on said frame, a pair of vertical rolls, housings for said vertical rolls movable in a horizontal plane on said frame, means for applying rotative power to each of said four rolls, and common means for moving said rolls in unison in relation to a common center, substantially as described.

4. In a blooming mill, the combination of a frame, housings in said frame slidable in vertical planes, other housings in said frame slidable in horizontal planes, a pair of horizontal rolls journaled in said first named housings, a pair of vertical rolls journaled in said second named housings, means for applying rotative power to each of said four rolls, and common means for shifting said housings whereby said rolls may be moved in unison in relation to a common center.

5. In a blooming mill, the combination of a frame, housings in said frame slidable in

vertical planes, other housings in said frame 30
slidable in horizontal planes, a pair of horizontal rolls journaled in said first named housings, a pair of vertical rolls journaled in said second named housings, said rolls being provided with beveled end portions 35
which bear together when the rolls assume their innermost positions, means for applying rotative power to each of said four rolls, and common means for shifting said housings, whereby said rolls may be moved in 40
unison in relation to their common center.

6. In a blooming mill, the combination of a frame, housings in said frame slidable in vertical planes, other housings in said frame 45
slidable in horizontal planes, a pair of horizontal rolls journaled in said first named housings, a pair of vertical rolls journaled in said second named housings, the necks of all of said rolls being provided with beveled gear teeth which intermesh whereby 50
said rolls rotate in unison, means for applying rotative power to one of said pairs of rolls, and common means for sliding said housings whereby said rolls may be shifted in unison in relation to a common center. 55

Signed at Pittsburgh, Pa., this 11th day
of Sept., 1920.

JOHN L. ALBIEZ.
